UNITED STATES PATENT OFFICE

131,165

DESIGN FOR A DISPLAY CASE

Paul M. Ressinger, Chicago, Ill.

Application August 14, 1941, Serial No. 102,839

Term of patent 14 years

To all whom it may concern:

Be it known that I, Paul M. Ressinger, a citizen of the United States, residing at Chicago, in the county of Cook and State of Illinois, have invented a new, original, and ornamental Design for Display Cases, of which the following is a specification, reference being had to the accompanying drawings, forming part thereof.

Fig. 1 is a front perspective view of a display case, showing my new design; and

Fig. 2 is a rear perspective view thereof, looking down from the top.

I claim:

The ornamental design for a display case, as shown.

PAUL M. RESSINGER.
